UNITED STATES PATENT OFFICE.

EUGENE VON VARGYAS, OF PITTSBURGH, PENNSYLVANIA, ASSIGNOR TO JAMES P. McLEAN AND WILLIAM F. HEIDENREICH, BOTH OF PITTSBURGH, PENNSYLVANIA.

COLLAPSIBLE RECEPTACLE.

1,021,853.

Specification of Letters Patent. Patented Apr. 2, 1912.

Application filed May 29, 1911. Serial No. 629,978.

To all whom it may concern:

Be it known that I, EUGENE VON VARGYAS, a subject of the King of Hungary, residing at Pittsburgh, in the county of Allegheny and State of Pennsylvania, have invented certain new and useful Improvements in Collapsible Receptacles, of which the following is a specification, reference being had therein to the accompanying drawing.

10 This invention relates to a collapsible receptacle, and more particularly to that type of receptacle commonly styled a "Foldable paper drinking cup."

The primary object of my invention is to furnish a paper drinking cup with a base that can be easily carried within the collapsible cup, when not in use and quickly attached to the bottom of the cup to provide a substantial base or support for the same.

20 Another object of my invention is to provide a base plate for flexible receptacles that can be placed in engagement with the folded edges of the receptacle to maintain the same upright and rigid.

25 A further object of my invention is to provide a drinking cup that can be used as an advertisement, easily carried and the parts thereof quickly assembled when it is desired to use the same, and a paper, par-

30 peroid or other flexible and waterproof material used in its construction.

In the manufacture of paper bags various modes are resorted to, and my invention relates particularly to bags or receptacles in which a properly shaped blank is cut out, and subsequently so folded over and pasted together at certain points, to form a receptacle.

35 I am aware of flexible paper drinking cups having been heretofore devised, and in carrying my invention into effect, I make use of that type of cup that is made from a long strip of paper of double the length of the bag to be formed, the strip of paper being folded upon itself and the edges cut to produce flanges that are adhesively connected to the edges of the blank, thus forming a receptacle having an open end and a solid or seamless bottom. The advantage of 45 using such a cup will hereinafter appear, and reference will now be had to the drawing, wherein there is illustrated a preferred embodiment of the invention, but it is to be understood that the structural elements thereof

are susceptible to such changes as fall within 55 the scope of the appended claims.

Figure 1 is a perspective view of the cup in a set-up position, Fig. 2 is a vertical sectional view of the same, Fig. 3 is a front elevation of the cup collapsed and partly 60 broken away to show the base plate therein, and Fig. 4 is an end view of the same.

As heretofore stated, the collapsible drinking cup is made of a single piece of material bent upon itself to provide walls 1 and 2, 65 one edge of the wall 2 having a flap or flange 3 adhesively secured to the edge of the wall 1, and this wall has a flap or flange 4 adhesively secured to the edge of the wall 2.

To spread the walls 1 and 2 apart to form a receptacle, the edges of the walls, adjacent to the lower ends thereof are pressed inwardly, to flatten the bottom of the receptacle, as at 5 and provide tapering tri-angu- 75 lar shaped oppositely disposed tongues 6.

The base for the receptacle comprises a disk 7 and riveted or otherwise connected to said disk, as at 8 are oppositely disposed segment-shaped retaining members 9 having the 80 straight edges thereof arranged in parallelism. The means employed for securing the members to the disk 7 are preferably located at the ends of said members, and the said members made of a flexible material, as 85 heavy cardboard, the tongues 6 can be easily slipped under the straight edges 10 of said members. It is preferable to make the members and the disk 7 of light and durable cardboard, although any other suitable ma- 90 terial can be used, and the receptacle is made of waterproof material, whereby a liquid can be held within the receptacle and supported by the base thereof.

When the cup is not in use and is col- 95 lapsed, the base is placed within the flattened cup and it is in this form that the cups can be disposed of, either for a small sum of money or as an advertisement.

In lieu of the segment-shaped members 9 100 straps can be used and in some instances the members can be formed integral with the disk 7, as would be the case if a strip of the cardboard had the ends thereof bent and riveted to the body of the strip.

105 As will be readily understood, by the use of either the segment-shaped members 9 or straps, pockets will be formed into which

the tongues of the collapsible portion of the cup pass.

What I claim is:—

1. In a drinking cup, a collapsible receptacle adapted to have the lower edges thereof bent to provide tongues, and a base detachably supported by the tongues of said receptacle.
2. In a drinking cup, a collapsible receptacle adapted to have the lower edges thereof bent to provide tongues, and a base of greater diameter than said receptacle, and adapted to be detachably connected to said tongues.
3. In a drinking cup, a collapsible receptacle, a disk, segment-shaped members

carried by said disk and adapted to hold oppositely disposed lower edges of said receptacle.

4. A drinking cup comprising a collapsible receptacle adapted to have the lower edges thereof bent to provide tongues, a disk adapted to support the bottom of said receptacle, and members mounted upon said disk and adapted to engage the tongues of said receptacle.

In testimony whereof I affix my signature in the presence of two witnesses.

EUGENE VON VARGYAS.
